UNITED STATES PATENT OFFICE.

FRED F. CHRISMAN, OF FULTON, NEW YORK, ASSIGNOR TO THE HUNTER ARMS COMPANY, OF SAME PLACE.

DESIGN FOR A FORK-CROWN FOR BICYCLES.

SPECIFICATION forming part of Design No. 25,281, dated March 24, 1896.

Application filed October 25, 1895. Serial No. 566,934. Term of patent 7 years.

To all whom it may concern:

Be it known that I, FRED F. CHRISMAN, a citizen of the United States, residing at Fulton, in the county of Oswego and State of New York, have invented and produced a new and original Design for a Fork-Crown for Bicycles; and I do hereby declare the following to be a full, clear, and exact description of the same, reference being had to the accompanying drawings, forming a part thereof.

Figure 1 is a side elevation of a bicycle-fork crown, showing my design; Fig. 2, a longitudinal sectional elevation of said crown; and Fig. 3 denotes a top plan thereof, said three representations being deemed advisable for the thorough illustrating of my design.

Like letters and figures of reference indicate corresponding parts throughout the views of the drawings.

20 The leading and particularly distinguishing feature of my design consists in the peculiar and balanced angularity of the crown-plate A, presenting a central truss-like portion slanting downward at its extremities into parallel horizontal end lengths, respectively, located upon a depressed or lower plane than that of the straight horizontal center of the truss-appearing portion mentioned, when viewed in side elevation, (either front or rear,) 25 as in Fig. 1, or in longitudinal section, as embodied by Fig. 2.

1 is the central portion of the fork-crown or plate A of an annular or ring shape in its general contour, as viewed in top or bottom plan; 2 2, the respective extremities of said crown in line and equidistant from the central portion 1, and each of an oval or oblong ring shape in general appearance, as viewed in top or bottom plan, while 3 3 indicate 30 widened level-surfaced ribs or connections longitudinally inclined or slanting, starting from opposite points of the boundary edges of the annular central portion 1, flat at its annular edges and connecting with the oval flat-ended rings 2 2, located on a horizontal plaque 35

differing from that level plane occupied by the central annular portion 1, as appearing viewed in top or bottom plan.

Viewed in side elevation my fork-crown A presents a horizontally straight outline, laterally rounded, as at a, outwardly, and downward inclines b b with smooth sides which terminate, respectively, in horizontally level outlines c c, located at a lower plane than the outline a and longitudinally rounded.

50 Protuberant downward from the central straight portion a appears a collar or longitudinally-rounded projection a', peripherally beveled and having a straight horizontal edge terminating it, while downward protuberant from the depressed straight outlines or extremities c c are collar-like or longitudinally-rounded portions c' c', beveling exteriorly and terminating in straight horizontal edges upon a plane lower than that of the horizontally straight bottom outline of the central portion hereinbefore described.

55 Obviously the angularity of formation, the longitudinally-rounded edges, the pendent rounded portions, the horizontally straight central outline connecting in opposite directions with shorter horizontally straight outlines located at a lower plane by intermediate inclined outlines create a pleasing and distinctive configuration and appearance to my 60 fork-crown for bicycles and insuring its being readily distinguished by reason of such unique outlines or configurations from others of this class.

Having described my design, what I claim 65 is—

The design for a fork-crown for bicycles, substantially as herein shown and described.

In testimony whereof I affix my signature, in presence of two witnesses, this 14th day of 80 October, 1895.

FRED F. CHRISMAN. [L. S.]
